UNITED STATES PATENT OFFICE

2,532,362

DEVICE FOR FORMING TROUSER CUFFS

Charles Halek, Cleveland, Ohio

Application October 2, 1947, Serial No. 777,530

9 Claims. (Cl. 223—37)

1

My invention relates to a trouser cuff forming apparatus.

It is one of the objects of the present invention to provide an apparatus of the type described which is extremely simple in construction, easy to operate, and which possesses the ability to form trouser cuffs of neat appearance and of uniform depth or width.

A further object of the invention is an apparatus of this kind which may be constructed of few parts and which may be operated by the foot of the operator, leaving the hands free to adjust the trouser leg on the device preliminary to forming the cuff and to temporarily pin or stitch the folds of the formed cuff in place before removing the same from the device for final stitching.

Another object of the invention is the provision of an apparatus of the above named character which is portable in its nature so that it may be moved readily to different locations in the shop.

Other objects and advantages in my invention will become more apparent as the following description of an embodiment thereof progresses, reference being made to the accompanying drawing in which like reference characters are employed to designate like parts throughout the same.

In the drawings:

Figure 1 is a vertical section through an apparatus embodying my invention, showing the same mounted on a table or other support,

Figure 2 is a front perspective view of the unassembled parts of the apparatus,

Figure 3 is a perspective view of the device shown in use to form a trouser leg cuff,

Figure 4 is an enlarged vertical section of the device showing a reversed trouser leg assembled on the device illustrating the first step in forming the cuff,

Figure 5 is a view similar to that shown in Figure 4, but, in addition, illustrates the second step in forming the cuff, as when the forming ring is applied, and,

Figure 6 is a view similar to the views shown in Figures 4 and 5, illustrating the final step in operating the apparatus to form the cuff, in which the forming cylinder has been elevated.

According to the embodiment of my invention illustrated in the drawing, the same may be supported on a table, bench or other support 1, thus rendering the device and support portable whereby it may be moved to any one of a number of convenient locations.

2

The device consists essentially of a cylinder 2 adapted to be supported on the table top, an insert forming ring 3, a slidable forming cylinder 4, and means for sliding the latter within the first mentioned cylinder and the ring.

In carrying out my invention, the forming cylinder 4 is mounted on the upper end of a rod 5 and is removably secured thereto by the nut 6 to move with the rod. The rod is adapted for reciprocating movement in the support 1 and terminates at its lower end in a pedal portion 7. A bearing member 8 is provided to slidably receive the rod on the support, while a coiled spring 9 encircling the rod normally urges the latter and the forming cylinder 4 to its uppermost position as shown in Figures 1, 2, 3 and 6. The lower end of the coil spring engages the bearing 8, while its upper end engages a washer 10 carried by the rod 5 below the bottom wall of the forming cylinder 4.

The cylinder 2 is adapted to be assembled over and to house the forming cylinder 4 in telescopic fashion, as illustrated in Figures 1, 4, 5 and 6, there being provided cooperating means on the support and on the cylinder 2 whereby the latter may be removably secured to the support when it is assembled over the cylinder 4. Such means may consist of substantially diametrically opposed bayonet slots 12 formed in the lower end 13 of the cylinder 2 for receiving the staples 11 positioned in the top surface of the support 1. It will be seen that the cylinder 2 may be locked in its supported position by causing the staples to enter the open slot and then turning the cylinder in one direction about its vertical axis.

The upper end of the cylinder 2 is formed with a flange 14 of slightly larger diameter than that of the cylinder body. The circumferential wall of the flange is preferably co-axial with the circular wall of the cylinder, but being of slightly larger diameter provides means therebetween for receiving the lower end of the trouser leg and the forming ring 3 as illustrated more particularly in Figures 5 and 6, at the same time offering no obstruction to the upward passage of the forming cylinder 4 as shown in Figure 6.

The flange 14 is provided with notches 15 formed at spaced intervals about its upper free edge for purposes which will be described hereinafter.

The forming ring 3 comprises a body portion having an outwardly extending peripheral flange 16 around its upper edge, the length of the body portion 3 being slightly less than the length of the flange wall 14 so that when the forming ring

is assembled in the cylinder 2, as in Figures 5 and 6, the flange 16 will engage and rest upon the trouser leg material 17, overlying the upper extremity of the flange 14, while at the same time there is provided a restricted space 18 between the trouser material and the lower end of the forming ring 3. It will further be noted that when the forming cylinder 4 is in its upper position in the cylinder 2, there is also provided a space 19 between the cylinder 4 and the ring 3 through which the material of the trouser leg is urged upwardly as the forming cylinder 4 is raised. This is illustrated more particularly in Figure 6.

In use, the invention may be described as operating substantially as follows: The cylinder 2 is telescoped over the forming cylinder 4 and is secured to the support 1 by rotating the cylinder 2 to interengage the bayonet slots 12 with the staples 13. This is illustrated more particularly in Figure 1. The operator then depresses the rod 5 by stepping on the pedal 7, and the cylinder 4 is thus withdrawn to its lowermost position, as shown in Figures 4 and 5, against the compression of the coil spring 9. While the rod is thus depressed, the material of the trouser leg which has been turned inside out, as shown in Figure 3, is slipped over the cylinder 2 and its cuff end is fed into the cylinder 2, the end portion overlying the top of the withdrawn forming cylinder 4, as illustrated in Figure 4.

It will be noted that the end of the trouser leg will overlie the cylinder 4 sufficiently to provide enough of the material for forming the cuff folds during the succeeding operations.

The forming ring 3 is then inserted into the upper flanged portion of the cylinder 2 until the peripheral flange 16 rests upon the trouser leg material lying over the top of the flange 14. The body of the ring 3 thereby serves to hold a portion of the trouser material between it and the flange 14, there being provided a space 18 between the lower end of the ring 3 and the transverse portion 20 of the cylinder 2.

The next step in the operation of the device resides in releasing foot pressure on the pedal 7 to allow the compression of the spring 9 to thrust the cylinder 4 upwardly within the cylinder 2 to a position substantially that indicated in Figure 6. During the upward movement of the cylinder 4 that portion of the trouser leg material overlying the cylinder 4, as in Figure 5, will be carried upwardly between the outer wall of the cylinder 4 and the inner wall of the ring 3, that is, within the space 19 formed therebetween. During this operation, of course, the ring 3 functions to hold the partially formed cuff in place in the apparatus.

That portion of the end of the trouser leg indicated at 21, which extends above the top of the cylinder 4 when the cylinder has reached its uppermost position, may then be folded down and over the top of the flange 16, and thence to overlie the unfolded portion of the trouser leg material 17. In this manner the folding of the cuff is completed, but before removing the trouser leg from the apparatus, it is desirable to baste or pin the folds in position so that the final sewing operation may be carried out in the usual manner.

Before temporarily securing the folds together, the ring 3 may be withdrawn from the apparatus by lifting the same axially therefrom. To enable the operator to pin or baste the folds into temporary position preliminary to final stitching, I

have provided in the cylinder 2 a plurality of spaced notches 15 opening upwardly along the upper edge of the cylinder, and of sufficient width to enable the operator to grasp the folds of the cuff between the fingers and either to pin or to baste them together. The cuff may then be removed from the apparatus.

From the above description it will be seen that I have provided an extremely simple apparatus for forming trouser cuffs, and which in its operation will form a cuff of uniform width or depth, quickly and easily.

Various changes may be made in the details of construction of the invention and the arrangement of parts, without departing from the spirit of the invention or the scope of the pending claims.

I claim:

1. In a trouser cuff forming apparatus, a cylinder, a forming cylinder movable axially in said first cylinder, means for moving said forming cylinder, and means independent of but insertable between said cylinders for guiding that portion of the material of a trouser leg from which a cuff is to be formed, into a plurality of folds when said forming cylinder is moved in one direction.

2. An apparel apparatus for forming cuffs comprising relatively movable co-axial cylinders, one of said cylinders adapted to receive that portion of the material of a trouser leg from which the cuff is to be formed, means independent of but insertable in said one cylinder for holding said material in place within said one cylinder, and another of said cylinders engageable with said material to fold it back upon itself and upon said means when said cylinders are subjected to relative axial movement.

3. An apparel apparatus for forming cuffs comprising relatively movable co-axial cylinders, one of said cylinders adapted to receive that portion of the material of a trouser leg from which the cuff is to be formed, means independent of but insertable in said one cylinder for holding said material in place within said one cylinder, and another of said cylinders engageable with said material to fold it back upon itself and upon said means when said cylinders are subjected to relative axial movement, and means for imparting relative axial movement to said cylinders.

4. An apparel apparatus for forming trouser cuffs comprising a pair of relatively movable cylinders, means for causing relative motion between said cylinders, and means insertable between said cylinders and spaced therefrom to provide a folding channel for that portion of a trouser leg on which a cuff is to be formed when said cylinders are relatively moved.

5. In a trouser cuff forming apparatus, a cylinder, a forming cylinder movable axially in said first cylinder, means for moving said forming cylinder, and means insertable between said cylinders for guiding that portion of the material of a trouser leg from which a cuff is to be formed, into a plurality of folds when said forming cylinder is moved in one direction, said first cylinder having a plurality of spaced notches formed in its periphery at its open end to provide access to said folded cuff whereby the folds thereof may be temporarily pinned or stitched before removing the same from the apparatus.

6. A trouser cuff forming machine comprising a base, a cylinder removably secured to the base and having an open upper end, said upper end having a diameter greater than the remainder

of said cylinder, a forming cylinder axially movable in said first cylinder, a forming ring insertable between said cylinders and being of a diameter less than that of the open end of said first cylinder but greater than that of the forming cylinder, and means for sliding said second cylinder in said first cylinder to a position opposite said ring.

7. A trouser cuff forming machine comprising a base, a cylinder removably secured to the base and having an open upper end, said upper end having a diameter greater than the remainder of said cylinder, a forming cylinder axially movable in said first cylinder, a forming ring insertable between said cylinders and being of a diameter less than that of the open end of said first cylinder but greater than that of the forming cylinder, and means for sliding said second cylinder in said first cylinder to a position opposite said ring, said first cylinder having a plurality of openings near its upper end to provide access laterally within said cylinder.

8. A trouser cuff forming apparatus comprising a support, a cylinder on said support and having an open upper end of a diameter greater than that of the remaining portion of the cylinder, a forming cylinder axially removable in said first cylinder, a forming member insertable between said cylinders, and means for moving

said second cylinder in said first cylinder to a position opposite said forming member.

9. A trouser cuff forming apparatus comprising a support, a cylinder on said support and having an open upper end of a diameter greater than that of the remaining portion of the cylinder, a forming cylinder axially removable in said first cylinder, a forming member insertable between said cylinders, said forming member being of cylindrical form and having an outwardly extending flange arranged to overlie the edge of the first cylinder defining its said open end when the said forming member is in assembled position in said first cylinder, and means for moving said second cylinder in said first cylinder to a position opposite said forming member.
